ANTENNA

Andrew Alford, Cambridge, Mass.

Application May 15, 1946, Serial No. 669,758

25 Claims. (Cl. 250—33)

1

This invention relates to new and useful improvements in radiators for vertically polarized waves.

Among the objects of this invention are: radiators and supporting structures, e. g. masts, of simple, inexpensive and yet rugged construction; small structures which are easy to install and maintain in service; and others whose nature will more clearly appear from a consideration of the problems that confronted the workers in this art, followed by a description of the way in which I have solved them.

Radio telephone, telegraph, facsimile, etc., communication, e. g. between fixed stations and mobile stations installed in automobiles, buses, etc., is usually effected on vertically polarized waves which have somewhat greater field intensity near ground and can be received on and transmitted by so-called "whip" antennas customarily employed on automobiles.

The fixed stations are usually provided with guyed steel tubular masts about 200 or 250 feet high and having a diameter of two to three and one-half inches within six to ten feet from the top and somewhat greater below, but usually not great enough to make the mast self-supporting. Therefore, sets of wire rope guys or the like are employed for holding the mast upright, self-supporting structures being too expensive.

A well known type of transmitting antenna which is mounted above the top of the mast consists of a vertical quarter-wave stub connected to the inner conductor of a coaxial transmission line, in combination with a quarter-wave tube. The upper end of the tube is connected directly to the outer conductor of the coaxial line. The lower end of the tube is insulated from the outer conductor so that high frequency currents flowing on the outer surface of the tube cannot continue directly down the mast but must pass through the space between the tube and the outer conductor. This arrangement is calculated to provide choking action to reduce the currents in the mast.

Among the shortcomings of such antenna are the following:

The choking action provided by the quarter-wave tube arrangement is insufficient to produce the required reduction in the mast currents which, therefore, will radiate a substantial portion of the total power. The power radiated by the mast may or may not be in proper phase with the antenna radiation in the horizontal direction, so that there may be a minimum of the total radiation in the horizontal directions and most of the power may be scattered in useless directions.

2

To rectify this undesirable condition, one or two additional quarter-wave chokes are frequently provided at suitable distances below the antenna. Since these chokes must be sharply tuned and are themselves radiating, the radiating system, consisting of the antenna and chokes, is multiply tuned and must be adjusted for proper relative phases and for proper choking action.

The antenna cannot be mounted below the top 10 of the mast. It is, therefore, impossible to increase the gain by stacking a number of such antennas.

Attempts have been made to design antennas consisting of two quarter-wave sleeves or of two 15 half-wave sleeves that could be installed concentrically around the mast. However, two quarter-wave sleeves are too sharply tuned and have a very low input impedance. Antennas consisting of two half-wave sleeves require a balanced high impedance feed of the order of 350 ohms which is impractical in many applications because of the 6 to 1 mismatch with the standard coaxial transmission line.

In accordance with the present invention, the 20 radiator or radiators are attached to a hollow body, in whose wall a transmission line is formed, the body itself constituting a radiator and an impedance-matching means between the feeder and the radiator or radiators.

One feature of the invention is that the transmission line is formed by a narrow gap—of the order of a small fraction of a wave length—in the wall of the body. The edges of this gap are preferably sharp and they form the transmission 35 line to which the feeder is connected.

In different embodiments of this invention the 40 role of this gap might be a different one with respect to the compensating action described hereinafter. In such embodiments it would not be expedient for the edges of this gap to be sharp. In fact the width of these edges for certain embodiments may be increased even beyond the thickness of the material forming the walls of the hollow body. The gap extends all around the 45 wall of the hollow body and returns on itself. Taking the feeder connecting points as the beginning—and end—of the gap, a short-circuiting bar bridges the mid-points of the edges of the gap.

In accordance with the present invention, the 50 hollow body may be fastened to a metal mast centrally with respect to the transmission line, without suffering the disadvantages to which I have referred.

In accordance with the present invention, the 55 dimensions of the body are such that transverse cross section taken in a plane through the axis

3

of the mast of the air space within said body on one side of the mast will have an area of about one-hundredth of a wave length squared, $.0105\lambda^2$. It is noted in this connection that the antenna is particularly suited for operating on a band of frequencies and that whenever, in the following description and claims, reference is made to wave length or frequency, the center frequency of said band is meant, unless, of course, a different meaning is indicated.

In the preferred embodiment here disclosed, the body is a cylinder in which the transmission line is formed, in accordance with a feature of this invention, in the form of a gap in the outside wall in a plane transverse to the axis of the cylinder and is short-circuited opposite its feed point. The cylinder has preferably a circular horizontal cross section, but this is not essential for all applications of the invention to good advantage. It should be understood, therefore, that the word "cylinder" as used in the description and claims, without further qualification, is intended to cover all hollow bodies suitable for the purposes of the present invention.

The cylinder serves as a radiator, a mechanical supporting means for attachment to a mast or the like, and an impedance-matching means. For a frequency band whose center is 378 mc., a cylinder $2\frac{1}{16}$ " high and 10" in diameter which has a $\frac{1}{16}$ " wide gap in a plane transverse to its axis, and which is axially traversed by a 1" steel tube through its center produces the desired results when equipped with four 7.5" radiators attached to each cylinder half and parallel with the axis of the tube, pairs of which project from opposite edges of said gap away from each other.

The nature of the invention will best be understood from the following description of an embodiment thereof as applied to the drawings in which Fig. 1 is a perspective of the antenna structure, and Fig. 2 a curve of the antenna on a 52-ohm line.

As shown in Fig. 1, the antenna consists of two circular body elements 1, 2 which may be castings or spinnings shaped like pie plates. The body elements consist of bottom discs 3, 4 having upstanding rims (bearing the above-mentioned numerals 1, 2) facing one another. These body elements 1, 2 are joined by means of a metal tube 5 which is mechanically attached to inside surfaces of bottoms 3 and 4 of elements 1 and 2 at substantially their centers. In practice, tube 5 may form part of either element 1 or 2, so that the assembly consists of only two pieces. Accordingly tube 5 may be made of a metallic and, as a result, of a conductive material. However, as will be obvious after the complete description of this device, the inside surface of tube 5 connects areas of zero (or extremely low) RF voltage of elements 1 and 2, and may, therefore, be non-conductive. While the inside of tube 5 need not be conductive for this device to operate, on the other hand it need not be non-conductive to keep any supporting structure, such as a mast through tube 5, from becoming energized with RF voltages. However, the outer surface of tube 5 should be conductive as there must be a low impedance axial connection between the inner surfaces of elements 1 and 2 and, if desired, a metallic mast may be used directly to perform this function. Tube 5 is of such length that body elements 1, 2 do not touch each other but are held so that their bottom discs 3 and 4 are parallel to one another and their rims are separated by gap 6. This gap is short-circuited by

4

metal band 7. Bottoms 3 and 4 have centrally located holes which register with the ends of the hole through 5. The structure 1-7 may be described as a hollow body or cylinder whose ends are closed by discs 3 and 4, and whose side wall has a gap 6 which runs around the cylinder in a plane parallel to and midway between the discs 3 and 4, and returns on itself. The cylinder halves are held together by coaxial tube 5 fastened to the inside of discs 3 and 4.

The structure of the hollow body or cylinder may be of material such as solid sheet metal or solid sheet plastic (with a conductive surface adhering thereto to achieve obvious electrical properties) and accordingly the interior space will be bounded by wall surfaces unbroken except for gap 6. However, this is not necessary. This device may alternatively be made of screen wire, of perforated sheet metal, or of perforated sheet plastic with a conductive surface. If the openings are not too large with respect to one wave length corresponding to the highest operating frequency, e. g. less than six one-hundredths of a wave length, the inner walls will be effectively unbroken electrically. Formulae relating to the limiting dimensions of such permissible openings are available in the literature.

The antenna is energized over a coaxial transmission line having an outer conductor 8 and inner conductor 9. The inner conductor 9 is connected to the rim of one of the two body elements, for example plate 1, and the outer conductor 8 is connected to the rim of the other. These connections are made at points diametrically opposite each other on gap 6 on the side of the hollow cylinder opposite to the short-circuiting band 7.

Four metal radiators formed as rods 10, 11, 12, 13 are conductively connected to the rim of element 1 and four similar rods 14, 15, 16, 17 are connected to the rim of element 2. These two sets of rods project away from bottoms 3 and 4 respectively at right angles to them and, therefore, parallel to the axis of tube 5.

When the antenna is mounted on a steel mast 18, the latter passes through the tube 5 and the holes in bottoms 3 and 4. The cylinder 1-7 is prevented from sliding up or down mast 18 by suitable collars or clamps such as 19-20. The coaxial transmission line 8, 9 may be suitably clamped to mast 18 and to element 2.

When the antenna is energized, the adjacent edges of the cylinder halves, i. e. the edges of 1, 2 forming gap 6, constitute a balanced transmission line. This line is loaded by a distributed reactance which depends on the area of a transverse cross section, taken in a plane through the axis of mast 18, of the air space enclosed on one side of tube 5 between the inner surfaces of elements 1, 2 and the outer surface of tube 5. If the inside radius of the hollow cylinder is designated as R , the outer radius of tube 5 as r , and the distance between the inner surfaces of bottoms 3 and 4 as H , then this cross-sectional area may be calculated from the formula $A=(R-r)H$. If these dimensions are converted into wave lengths and the formula solved, $A=.0105\lambda^2$.

Short-circuiting band 7 produces nearly complete reflection of waves traveling along gap 6, and the interference between direct traveling waves and reflected traveling waves results in a standing wave distribution of voltage across gap 6. One minimum of voltage across the gap occurs at short-circuiting band 7; two maxima of voltage occur at points on gap 6 on opposite sides of the

5

hollow cylinder each of which is about between 7 and the diametrically opposite point where the coaxial cable connection is made. Two additional voltage minima under certain conditions may occur a short distance from and on each side of the point of connection of the concentric line.

Substantially one-half of the respective voltage differences between the edges of gap 6 at the points where radiators 10, 11, 12, 13 . . . 17 are connected are applied respectively to one end of each radiator, causing them to operate as vertical radiators. Since the voltages existing across the gap between minima are substantially in the same phase for different points along that portion of the gap, and since, when this device is properly proportioned and adjusted, the only points of minima are in the region of the feed point and at the shorting band, all the upper rods 10-13 are energized in the same phase and all lower rods 14-17 are energized in the opposite phase.

It is noted that the second minima need not coincide with the feed point and that preferably they should be at imaginary points beyond the feed point rather than between it and the shorting band.

Thus, hollow cylinder 4-7 serves as a means for obtaining balanced, equal and opposite voltages and, at the same time, it operates as a transformer which matches the combined impedances of radiators 10-17 to the impedance of the coaxial transmission line feeder 8, 9. In addition, the cylinder serves as a supporting means for radiators 10-17.

Typical proportioning of the several parts of the antenna may be as follows: $D=.32\lambda$, $d=.032\lambda$, $H=.072\lambda$, $g=.0048\lambda$, $L=.236\lambda$. The dimensions are here as well as in the drawings given in terms of the operating wave length at the frequency which is at the center of the band of frequencies. The antenna so proportioned is substantially matched to a 50 ohm coaxial transmission line within said frequencies and the second voltage minima are properly located. The dimensions in inches would be as follows at the geometric means frequency of 378 mc.: $D=10''$, $d=1''$, $H=2\frac{3}{16}''$, $g=\frac{1}{16}''$, $L=7.5''$.

Fig. 2 shows a measured standing wave ratio as a function of frequency for the antenna having the above proportions.

The following considerations control the proportioning of the antenna. The voltage distribution along the gap 6 should be such that the radiators 10-17 are energized in the same phase. Since the phase of the voltage varies rapidly in the region of a voltage minimum except at the short-circuiting band 7 and the feed point, it is desirable to have the proportions and electrical behavior of the cylinder such that there are no other minima or that any such other minima of voltage occur between any radiators near the feed point and the feed point, or even at still greater distances from the short-circuiting band 7 even to imaginary points beyond the feed point. When voltage minima occur in the neighborhoods of two pairs of radiators, then the voltages applied to the other pairs of radiators are higher than the voltages applied to the first pairs. This condition is ordinarily not desirable because it causes some asymmetry in the horizontal radiation pattern, distorting it from a circle. More desirable proportioning is obtained when the distance from band 7 to the first voltage minimum or to the first imaginary minimum along the gap in each direction around the hollow cylinder is equal to (or is greater than) one-half of the circumference of

6

the cylinder because, then the voltages applied to each pair of radiators located between the shorting band and such a minimum are nearly equal. If, moreover, the two sides of each cylinder half have standing waves of equal magnitude, this will result in a substantially circular radiation pattern.

The voltage distribution along the gap 6 depends on two factors: The circumference of the hollow cylinder, i. e. the gap length, and the velocity of propagation along the edges of the gap. The gap length can be increased by increasing the propagation velocity. The propagation velocity is controlled by the cross-sectional area A and the capacity per unit length between the edges of the gap. A cross-sectional area, $A=.0105\lambda^2$, together with a gap which is a small fraction of a wave length wide (.0048 λ), and is formed by thin metal edges, results in a velocity of propagation along the gap about 20% greater than the velocity in free space. This permits the use of a hollow cylinder of large circumference and results in a good impedance match.

The effect of the addition of radiators on the voltage distribution along the gap depends in part on their length in comparison with the operating wave length. When each of the individual radiators is approximately one-quarter wave length long and the input impedance of each radiator is resistive, there is little effect on the distances between the first voltage minima and short-circuiting band 7.

Below the center of the band of operating frequencies, the radiators are less than one-quarter wave length long and the impedance of the radiators is capacitative. The effect of shunting a capacitative impedance across the gap is to decrease the velocity of propagation and, therefore, to shorten the distance between short-circuiting band 7 and the first voltage minima.

Above the center frequency, the radiators are longer than a quarter wave length and their input impedances are inductive. The effect of shunting an inductive impedance across the gap is to accelerate the velocity of propagation and, therefore, to increase the distance from band 7 to the first voltage minima.

The over-all effect of the radiators is thus beneficial in that at frequencies below the center frequency of the antenna the capacitative impedance of the radiators lowers the effective propagation velocity which, without radiators, due to changes in the behavior of the hollow cylinder when frequency changes, would be too high. At frequencies above the center frequency the inductive impedance of the radiators accelerates the velocity of propagation which, without radiators, would become too low. This compensating effect of the radiators is important in maintaining the desirable voltage distribution across the gap over a wide band of frequencies. The nearly constant voltage distribution assures the application of nearly equal relative voltages to the four pairs of radiators and results in a substantially circular horizontal pattern which is maintained over a wide band of frequencies. Furthermore, the input impedance presented to the coaxial feeder is maintained near the desired value of 50 ohms over a substantial frequency band, because the positions or imaginary positions of the voltage minima remain nearly constant with respect to the feed point.

In the above discussion of the theory of operation of the antenna it has been indicated that the cylinder halves need not be of solid metal, but

may have holes or may be made of wire netting. Moreover, their transverse cross sections need not be circular but may be square, elliptical, or of some other shape. I use, therefore, in the specification and claims the word "cylinder" in a broad sense to include all such alternatives. Furthermore, it is possible to use more than four pairs of radiators. When only two radiators are used, the pattern is no longer circular but deviations from a circular pattern may be desirable in some applications.

When all radiators 10-17 are removed, the hollow cylinder itself will continue to radiate, but this may produce appreciable currents in the supporting mast 18, particularly if its diameter and that of tube 5 is large. When radiators are added, the mast currents are noticeably reduced and, moreover, because of the compensating action of the radiators, the band width of the antenna is substantially increased.

My improved antenna produces a substantially circular radiation pattern in the horizontal plane and a figure of eight pattern in vertical planes through supporting mast 18. The antenna may be mounted at any desired distance from the top of the tubular metal mast and, therefore, may be used as one element in a vertical array consisting of several similar antennas. The antenna has a wide band and easily matches the customary 50 ohm coaxial transmission line 8, 9 without the aid of transformers or balancing circuits. The currents induced by the antenna in the supporting mast 18 are too small to require any chokes or carefully chosen spacings between the antenna and guy points or points of other high frequency discontinuity. The antenna unit is so constructed that coaxial feeders similar to coaxial feeder 8, 9 may be conveniently passed through it (e. g. through tube 5) to other similar units also attached to the mast. Moreover, such coaxial feeders may even pass through the interior of the hollow body next to the outside surface of tube 5 and due to their small size with respect to the cross-sectional area of the hollow body they will not hamper normal performance.

The antenna offers small resistance to wind and does not require a heavy mast for its support. Furthermore, openings like gap 6 may be easily sealed off against the elements by an insulating material and this will also strengthen the unit.

Obviously, the antenna of the present invention may be employed at frequencies and for purposes different from those here given by way of exemplification. For instance, where masts must be kept very low, the hollow body of this antenna might be employed even at broadcast frequencies without radiators added thereto.

What I claim is:

1. In an antenna, a conducting cylinder transversely divided into two parts by a circumferential gap, internal means for conductively interconnecting the two parts, means for feeding the cylinder at the circumferential gap to produce balanced, equal and opposite voltages along opposed portions of its two parts, and radiators electrically connected to said two parts and supported by the cylinder which matches their impedance to that of the means for feeding.

2. In an antenna, a conductive cylinder transversely divided into top and bottom parts, internal means for conductively interconnecting the two parts, the area of a cross section of the interior space of the cylinder in a plane through the axis thereof and bounded by its interior surface and the outer surface of said means for interconnect-

ing and lying on one side of said means for interconnecting being substantially .0105², means for feeding the cylinder to produce balanced, equal and opposite voltages between its two parts, and radiators substantially one-quarter wave length long conductively supported by the cylinder where said voltages occur, said cylinder matching their impedance to that of the means for feeding.

3. In an antenna for a band of vertically polarized waves, a cylindrical metal body divided into two parts by a circumferential gap about the cylinder, means for feeding the body to produce balanced, equal and opposite voltages in its two parts, and radiators metallically supported by the cylinder which matches their impedance to that of the means for feeding, said radiators being substantially one-quarter wave length long at the center frequency and having resistive input impedances at that frequency.

4. In an antenna for a band of vertically polarized waves, a conducting cylinder having a gap interrupting the conductivity of its surfaces in a plane transverse to its axis, metal discs closing the ends of the cylinder, a conductive tube axially located within the cylinder and electrically and mechanically connecting the discs, a short-circuiting bar across the gap, a feeder connected with the edges of the gap in the cylinder at points on the side of the cylinder diametrically opposite to the position of said short-circuiting bar, and conductive radiators fastened to the cylinder near to the gap.

5. The antenna according to claim 4, and in which the velocity of propagation along the gap is substantially twenty percent greater than in free space.

6. In an antenna, a hollow cylinder having electrically conductive surfaces, a balanced transmission line formed by a gap in the side wall and which interrupts its conductivity which is in a plane transverse to the longitudinal axis of the cylinder midway between its ends, a feeder connected with said line, a short circuiting means for the transmission line at a point on said cylinder diametrically opposite the point of connection of the feeder, said cylinder and said transmission line being proportioned to cause a velocity of propagation along the transmission line substantially twenty percent greater than in free space, and radiators attached to said side walls adjacent to said transmission line and projecting beyond each end of the cylinder.

7. In an antenna for radiating a band of frequencies, a conducting cylinder, a balanced transmission line formed in the side wall of the cylinder midway between its ends and in a plane transverse to the longitudinal axis of the cylinder, a feeder connected with said line, a short circuiting means for the transmission line at a point on said side wall diametrically opposite to the point of connection of the feeder, and radiators electrically connected to the transmission line and projecting from each end of the cylinder and having a resistive input impedance at the center frequency.

8. In an antenna, a conducting cylinder having an internal diameter of substantially a third of a wave length and an internal height of about a fifteenth of a wave length, the ends of the cylinder being electrically closed by conducting base plate elements, an internal electrical connection between said base elements along the longitudinal axis of the cylinder, the outside dimension of said connection being substantially one-tenth of said diameter, a balanced transmission line formed by a gap in the side wall of the cylinder, which lies

in a plane transverse to its longitudinal axis and interrupts its conductivity midway between its ends, a feeder for said line comprising a concentric cable connected with the edges of said gap, a short-circuiting means for the transmission line conductively connecting the edges of the gap at a point diametrically opposite the point of connection of the feeder and producing a standing wave distribution having one minimum at the short circuit, another minimum at the point of connection of the cable, and two maxima between said minima on opposite sides of the cylinder and an equal number of rods amounting to at least four attached to each edge of said gap projecting substantially a quarter wave length from each end of the cylinder parallel with its axis and so positioned along said gap that nearly equal relative voltages are applied thereto, and that substantially equal halves of the voltage differences existing across the transmission line at points where rods are attached are applied to ends of opposed pairs of rods attached to opposite edges of the gap whereby the rods operate as vertical radiators, the rods projecting from one end being energized in one phase and the other rods in the opposite phase.

9. In an antenna for vertically polarized waves, a conducting cylinder having a large diameter compared to its height, conducting discs closing the ends of the cylinder, said cylinder having a narrow gap in a plane parallel with and midway between the discs and extending around the side wall, a short-circuiting bar across the gap, a conducting connection axially located within the cylinder between the discs, a feeder connected with the edges of the gap at points diametrically opposite said short-circuiting bar, and metal rods fastened to the edges of the gap and to each cylinder half and projecting therefrom parallel with the axis of the connection.

10. In an antenna for vertically polarized waves, a cylinder having conducting inner surfaces, conducting discs closing the ends of the cylinder, a conducting tube axially located within the cylinder and conductively connecting the discs, the cross-sectional area of the toroidal space between the outside of the tube and the inner surfaces of the cylinder being substantially $.0105\lambda^2$, said cylinder being separated into two parts to define a non-conducting gap substantially $.0048\lambda$ wide around the side wall of the cylinder in a plane parallel with and midway between the discs, a short-circuiting bar across the gap, a feeder electrically connected with the edges of the gap at points diametrically opposite said short-circuiting bar, and metal rods electrically connected to each edge of the gap and projecting in space parallel with the axis of the tube to a distance of substantially one-quarter wave length.

11. In an antenna for vertically polarized waves, a metal cylinder having an internal diameter of substantially one-third of a wave length and an internal height of substantially one-fifth of the diameter, metal discs closing the ends of the cylinder, said cylinder having a gap a small fraction of a wave length wide in a plane parallel with and midway between the discs extending around the side wall of the cylinder, a short-circuiting bar across the gap, a metal tube having substantially one-tenth the diameter of the cylinder axially located within the cylinder and metallically connecting the discs, a concentric cable having an outer conductor connected with one edge of the gap and an inner conductor connected with the other edge of the gap at a point on said

gap diametrically opposite said short-circuiting bar, and four metal rods fastened to each edge of said gap and projecting in free space away therefrom in opposite directions parallel with the axis of the tube to a distance of substantially one-quarter of a wave length.

12. In an antenna for radiating a band of vertically polarized waves, a metal cylinder enclosing a volume of space $.072\lambda$ high and having a diameter of $.32\lambda$, cross sections of said cylinder in planes transverse to its axis being circular, centrally perforated metal discs closing the ends of the cylinder, the side wall of the cylinder having a gap $.0048\lambda$ wide extending around the cylinder in a plane parallel with and midway between the discs, a short-circuiting bar across the gap, a metal tube having an outer diameter of $.032\lambda$ axially located within the cylinder and metallically connecting the discs, said tube having the ends of the annular channel through it in alignment with the perforations, a concentric cable having an outer conductor connected with one-half and an inner conductor connected with the other half of the cylinder at points on the edges of said gap which are diametrically opposite said short-circuiting bar, a hollow metal mast projecting through said tube and perforations supporting said cylinder, and four metal rods fastened to each edge of the gap at substantially equally spaced intervals at points where nearly equal relative voltages are applied thereto, said rods projecting away from the corresponding discs and parallel with the mast to a distance of substantially $.236\lambda$ into free space.

13. In an antenna, a hollow conducting body having its internal surface boundaries substantially defining a toroidal shaped space, said hollow conducting body forming an air gap extending about the toroidal shaped space on its outer side forming with the conducting material adjacent either side of the air gap a transmission line and a feeder having one line connected to the conducting material adjacent the air gap on one side and another line connected to the conducting material opposite the connection of the first line on the other side of the air gap.

14. In an antenna, a hollow conducting body having its internal surface boundaries substantially defining a toroidal shaped space, said hollow conducting body forming an air gap extending about the toroidal shaped space on its outer side forming with the conducting material adjacent either side of the air gap a transmission line and a feeder having one line connected to the conducting material adjacent the air gap on one side and another line connected to the conducting material opposite the connection of the first line on the other side of the air gap, and a short circuit member connected across the air gap spaced away from the position where the feeder is connected to the conductor material at either side of the air gap.

15. In an antenna, a hollow conducting body having its internal surface boundaries substantially defining a toroidal shaped space, said hollow conducting body forming an air gap extending about the toroidal shaped space on its outer side forming with the conducting material adjacent either side of the air gap a transmission line and a feeder having one line connected to the conducting material adjacent the air gap on one side and another line connected to the conducting material opposite the connection of the first line on the other side of the air gap, and a short circuit member connected across the air gap diametrically opposite the position where the feeder

is connected to the conductive material at either side of the air gap.

16. In an antenna, a hollow conducting body having its internal surface boundaries substantially defining a toroidal shaped space, said hollow conducting body forming an air gap extending about the toroidal shaped space on its outer side forming with the conducting material adjacent either side of the air gap a transmission line and a feeder having one line connected to the conducting material adjacent the air gap on one side and another line connected to the conducting material opposite the connection of the first line on the other side of the air gap and a plurality of radiators projecting from the conductive body at spaced intervals adjacent the air gap.

17. In an antenna, a hollow conducting body having its internal surface boundaries substantially defining a toroidal shaped space, said hollow conducting body forming an air gap extending about the toroidal shaped space on its outer side forming with the conducting material adjacent either side of the air gap a transmission line and a feeder having one line connected to the conducting material adjacent the air gap on one side and another line connected to the conducting material opposite the connection of the first line on the other side of the air gap, a short circuit member connected across the air gap spaced away from the position where the feeder is connected to the conductive material at either side of the air gap, and a plurality of radiators projecting from the conductive body at spaced intervals adjacent the air gap.

18. In an antenna, a hollow conducting body having its internal surface boundaries substantially defining a toroidal shaped space, said hollow conducting body forming an air gap extending about the toroidal shaped space on its outer side forming with the conducting material adjacent either side of the air gap a transmission line and a feeder having one line connected to the conducting material adjacent the air gap on one side and another line connected to the conducting material opposite the connection of the first line on the other side of the air gap, a short circuit member connected across the air gap diametrically opposite the position where the feeder is connected to the conductive material at either side of the air gap and a plurality of radiators projecting from the conductive body at spaced intervals adjacent and on opposite sides of the air gap.

19. In an antenna, a hollow conducting body having its internal surface boundaries substantially defining a toroidal shaped space, said hollow conducting body forming an air gap extending about the toroidal shaped space on its outer side forming with the conducting material adjacent either side of the air gap a transmission line and a feeder having one line connected to the conducting material adjacent the air gap on one side and another line connected to the conducting material opposite the connection of the first line on the other side of the air gap and a plurality of radiators projecting from the conductive body at spaced intervals adjacent the air gap, said air gap lying substantially in a plane and the radiators extending normally to said plane.

20. In an antenna, a hollow conducting body having its internal surface boundaries substantially defining a toroidal shaped space, said hollow conducting body forming an air gap extending about the toroidal shaped space on its outer side forming with the conducting material ad-

jacent either side of the air gap a transmission line and a feeder having one line connected to the conducting material adjacent the air gap on one side and another line connected to the conducting material opposite the connection of the first line on the other side of the air gap, and a support for said conductive body passing transversely through the same.

21. In an antenna, a hollow conducting body having its internal surface boundaries substantially defining a toroidal shaped space, said hollow conducting body forming an air gap extending about the toroidal shaped space on its outer side forming with the conducting material adjacent either side of the air gap a transmission line and a feeder having one line connected to the conducting material adjacent the air gap on one side and another line connected to the conducting material opposite the connection of the first line on the other side of the air gap, a short circuit member connected across the air gap diametrically opposite the position where the feeder is connected to the conductive material at either side of the air gap, a plurality of radiators projecting from the conductive body at spaced intervals adjacent and on opposite sides of the air gap and a support for said conductive body passing transversely through the same.

22. In an antenna, a hollow conducting body having its internal surface boundaries substantially defining a toroidal shaped space, said hollow conducting body forming an air gap extending about the toroidal shaped space on its outer side forming with the conducting material adjacent either side of the air gap a transmission line and a feeder having one line connected to the conducting material adjacent the air gap on one side and another line connected to the conducting material opposite the connection of the first line on the other side of the air gap, a short circuit member connected across the air gap diametrically opposite the position where the feeder is connected to the conductive material at either side of the air gap, said air gap lying substantially in a plane, a plurality of radiators projecting from the conductive body at spaced intervals adjacent and on opposite sides of the air gap and perpendicular to said plane and a conductive mast passing through the conductive body and parallel to said radiators.

23. In an antenna, a hollow conducting body having its internal surface boundaries substantially defining a toroidal shaped space, said hollow conducting body forming an air gap extending about the toroidal shaped space on its outer side forming with the conducting material adjacent either side of the air gap a transmission line and a feeder having one line connected to the conducting material adjacent the air gap on one side and another line connected to the conducting material opposite the connection of the first line on the other side of the air gap, a short circuit member connected across the air gap spaced away from the position where the feeder is connected to the conductive material at either side of the air gap and means including said conductive body for electrically loading said line with distributed reactance.

24. In an antenna, a hollow conducting body having its internal surface boundaries substantially defining a toroidal shaped space, said hollow conducting body forming an air gap extending about the toroidal shaped space on its outer side forming with the conducting material adjacent either side of the air gap a transmission

line and a feeder having one line connected to the conducting material adjacent the air gap on one side and another line connected to the conducting material opposite the connection of the first line on the other side of the air gap, a short circuit member connected across the air gap spaced away from the position where the feeder is connected to the conductor material at either side of the air gap, and a plurality of radiators projecting from the conductive body at spaced intervals adjacent the air gap, said antenna adapted to transmit with substantially uniform amplitude a short wave frequency band with a resistive input impedance at the center frequency, a capacitative input impedance below and an inductive input impedance above the center frequency.

25. In an antenna, a hollow conducting body having its internal surface boundaries substantially defining a toroidal shaped space, said hollow conducting body forming an air gap extending about the toroidal shaped space on its outer side forming with the conducting material adjacent either side of the air gap a transmission line and a feeder having one line connected to the conducting material adjacent the air gap on one side and another line connected to the

conducting material opposite the connection of the first line on the other side of the air gap, a short circuit member connected across the air gap spaced away from the position where the feeder is connected to the conductive material at either side of the air gap, a plurality of radiators projecting from the conductive body at spaced intervals adjacent and on opposite sides of the air gap whereby substantially equal relative but oppositely phased voltages may be applied to the radiators projecting from the transmission line gap in substantially the same direction.

ANDREW ALFORD.
